UNITED STATES PATENT OFFICE.

JULIUS M. SINGER, OF DETROIT, MICHIGAN, ASSIGNOR TO WOLVERINE BOTTLING WORKS, OF DETROIT, MICHIGAN, A COPARTNERSHIP COMPRISING JULIUS M. SINGER AND MAX SEDMAN.

DESIGN FOR A BOTTLE.

Application filed July 7, 1924. Serial No. 10,081. Term of patent 7 years.

To all whom it may concern:

Be it known that I, JULIUS M. SINGER, a citizen of the United States, residing at Detroit, in the county of Wayne and State of Michigan, have invented a new, original, and ornamental Design for a Bottle, of which the following is a specification, reference being had to the accompanying drawing, forming part thereof.

In the accompanying drawing,

Fig. 1 is a side elevation of the design for a bottle.

Fig. 2 is a cross-sectional view on line 2—2 of Figure 1.

Fig. 3 is a cross-sectional view on line 3—3 of Figure 1.

I claim—

The ornamental design for a bottle as shown.

JULIUS M. SINGER.
